CLAIM

The ornamental design for a driving belt as shown and described.

DESCRIPTION

1. Driving belt

2. Driving belt

1.1 : Top

1.2 : Bottom

1.3 : Front

1.4 : Back

1.5 : Left

1.6 : Right

1.7 : Perspective

2.1 : Top

2.2 : Bottom

2.3 : Front

2.4 : Back

2.5 : Left

2.6 : Right

2.7 : Perspective

Figure 1.1: top plane view of detail of a driving belt; Figure 1.2: bottom plane view of detail of a driving belt; Figure 1.3: front view of driving belt; Figure 1.4: rear view of driving belt; Figure 1.5: left side view of driving belt; Figure 1.6: right side view of driving belt; Figure 1.7: perspective view of driving belt; Figure 2.1: top plane view of detail of a driving belt; Figure 2.2: bottom plane view of detail of a driving belt; Figure 2.3: front view of driving belt; Figure 2.4: rear view of driving belt; Figure 2.5: left side view of driving belt; Figure 2.6: right side view of driving belt; Figure 2.7: perspective view of driving belt. Broken lines depict portions of the driving belt which form no part of the claimed design. The article is shown with a symbolic break

(Continued)

in its length. The appearance of any portion of the article between the break lines forms no part of the claimed design.
